UNITED STATES PATENT OFFICE.

GEORGE A. STEINER, OF SALT LAKE CITY, UTAH, ASSIGNOR TO STEINER SALES COMPANY, OF SALT LAKE CITY, UTAH, A CORPORATION OF UTAH.

ATTACHMENT FOR TOWEL CABINETS.

Application filed August 20, 1923. Serial No. 658,326.

In the use of a roller towel cabinet, the depending loop of toweling is grasped by the user and pulled down to bring the clean section of the towel to a point convenient for use, and when the wiping operation is finished, a loop of the towel depends a considerable distance below the cabinet, and the used or soiled portion of the towel is usually visible and presents an unattractive appearance in the room where the cabinet is located.

The object of my invention is to provide a take-up device for the towel cabinet which will have the function of shortening or drawing up the first loop and forming another loop of the soiled towel in the rear thereof which will be largely concealed by the forward loop.

A further object is to provide a take-up device which can be easily and quickly applied to a cabinet; either a new one in process of construction or an old one that has been in use.

Other objects of the invention will appear from the following detailed description.

In the accompanying drawings forming part of this specification,

Figure 1 is a vertical sectional view through a roller towel cabinet embodying my invention;

Figure 2 is a side view of the same;

Figure 3 is a front view; and

Figure 4 is a detail sectional view illustrating a modified construction of the take-up device.

In the drawing, 2 represents the front of the cabinet; 3, the rear thereof, and 4 and 5, the clean and soiled towel rolls mounted in guides 6 and 7 in the side walls of the cabinet. 8 and 9 represent sanded feed rolls mounted to contact respectively with the clean and soiled towel rolls and having a driving connection 10 between them for simultaneous movement. 11 is a plate closing the bottom of the cabinet; 12 is a guide hinged at 13 and separated from the rear wall by a space 14 through which the soiled towel is fed upwardly to its roll. 15 is a bracket secured by suitable means to the plate 11; and 16 is a frame centrally pivoted at 17 in the bracket 15 and supporting a comparatively light roll 18 and a comparatively heavy roll 19 which engage the web of the towel upon opposite sides of the pivot 17.

The clean towel is fed downwardly

through an opening 20 at the front of the cabinet, and passes over a roll 21 which has the function of holding the towel web forwardly within convenient reach of the user and preventing it from coming in contact with the soiled portion of the web.

When the user grasps the clean towel and pulls downwardly and forwardly thereon, the clean towel roll will be unwound to deliver a section of clean towel and at the same time, the frame 16 will be oscillated on its pivots from the position shown in Figure 1, to that illustrated in Figure 2, allowing the user to have free use of the depending towel loop, but as soon as the towel web is released, the weight of the roll 19 will swing the frame 16 to the position indicated in Figure 1; the roll 18 lifting up on the towel web and the roll 19 exerting a downward pull thereon and both cooperating to shorten the forward loop of the towel and conceal the used or soiled portion. With this device, it is not necessary to have the roll 19 drop as far below the cabinet, and consequently the device does not take up as much room on the cabinet as it would if only a single loop was formed in the rear of the main loop.

A device for making a single loop, however, would be entirely practicable and I have illustrated such a construction in Figure 4, in which 22 represents the bracket secured to the portion of the bracket and supporting a gravity roll 24 under which the soiled web passes; the weight of this roll normally tending to draw up the soiled web and shorten the loop at the front of the cabinet. The roll 25 is preferably mounted in the bracket 22 over which the towel web passes and operates to support the rear stretch of the forward loop.

When the user pulls the loop forward to the position, indicated by dotted lines in Figure 4, the frame 23 will be raised and as soon as the loop is released, the frame will drop, drawing up the soiled web to a point where a considerable portion of it will be substantially concealed. This device is capable of application to a cabinet in use as well as one that is in process of construction, and in either case will serve as a means for looping and concealing an unsightly section of soiled towel.

I claim as my invention:

1. A towel cabinet comprising a casing, clean and soiled towel rolls mounted there-

- in, and a driving means for said rolls, a loop of the clean towel depending through the bottom of said casing within convenient reach of the user, a bracket secured to the 5 lower portion of said casing, a frame centrally pivoted in said bracket to oscillate therein, a comparatively light roll provided at one end of said frame, a comparatively heavy roll mounted in the other end 10 of said frame, said rolls engaging the towel web, and said heavy roll normally tending to swing downward to a depressed position, and exert an upward or lifting movement on the towel on one side of the pivot of said 15 frame and a downward pull upon the towel on the other side of the pivot of said frame.
2. A towel cabinet comprising a casing adapted to contain a web of toweling, a loop of clean towel depending below the bottom 20 of said casing within convenient reach of the user, a frame centrally pivoted below said casing, a comparatively light roll mounted in one end of said frame, a comparatively heavy roll mounted in the other end of 25 said frame, said rolls engaging the towel web and said heavy roll normally tending to swing downwardly to a depressed position and exert an upward or lifting movement on the towel on one side of the pivot of said 30 frame, and a downward pull upon the towel on the other side of the pivot of said frame.
3. A towel cabinet comprising a casing adapted to contain a web of toweling, a loop of clean towel depending below the bottom 35 of said casing within convenient reach of the user, a roll pivotally supported below said

casing and adapted to engage the web of towel, a guide over which the web of towel passes to said pivoted roll, said pivoted roll being comparatively heavy and adapted to 40 raise the depending loop of towel when the user releases his grasp thereon, whereby the soiled portion of the towel will be lifted to an inconspicuous position beneath the cabinet. 45

4. A towel cabinet comprising a casing, clean and soiled towel rolls mounted therein and a feeding means therefor, a loop of the clean towel depending within convenient 50 reach of the user, and an oscillating take-up frame having a weighted roll that is raised by the pull of the user on the towel web for lifting a portion of the web to an inconspicuous position when the pull of the user thereon is released. 55

5. A towel cabinet comprising a casing having means for delivering a web of clean towel and returning to the cabinet the web of soiled towel as it is used, a loop of the clean toweling normally depending below the casing, and means engaging the web of towel and adapted to be tilted when the user exerts a downward pull on the towel web to allow the length of the loop to be temporarily increased, said means automatically returning to its normal position and raising the soiled portion of the towel to an inconspicuous position beneath the casing when the user releases his grasp thereon. 60

In witness whereof, I have hereunto set 70
my hand this thirteenth day of August, 1923.

GEORGE A. STEINER.
